Thomas J. Vunak
Anton Arnold

UNITED STATES PATENT OFFICE.

FRANCIS MLEKUSH, OF RANKIN, PENNSYLVANIA.

SMOKER.

1,328,183.

Specification of Letters Patent. Patented Jan. 13, 1920.

Application filed July 25, 1919. Serial No. 313,165.

To all whom it may concern:

Be it known that I, FRANCIS MLEKUSH, a citizen of the United States, residing at Rankin, in the county of Allegheny and 5 State of Pennsylvania, have invented new and useful Improvements in Smokers, of which the following is a specification.

This invention relates to smokers, and more particularly to a device intended to 10 cure meat and similar articles of food by smoking in the known manner.

One of the main objects of the invention is to provide a device of the character stated of simple construction and operation which 15 may be readily produced at small cost. Another object is to provide a smoker specially adapted to domestic use which is so constructed as to reduce the danger of fire to a minimum. Further objects will appear 20 from the detailed description.

In the drawings:—

Figure 1 is a front view of a smoker constructed in accordance with my invention.

Fig. 2 is a central vertical sectional view 25 through the smoker, the door being open.

In constructing my smoker I provide a sheet metal casing 1 of rectangular cross section which is supported and reinforced by corner angle strips 2. This casing is 30 provided in its front wall with a doorway or opening adapted to be closed by a door 3 hingedly secured to the casing, this door being normally held in closed position by a turn button 4. A short distance from its 35 lower end, the casing is provided with two perforated plates 5 which extend the full cross area thereof, these plates being spaced apart to form a smoke cooling and smoke and air mixing compartment 7. Air is admitted to this compartment through openings 8 in the front and side walls of the casing, these openings being covered by screen wire of fine mesh. The front wall of the casing, at the lower end thereof, is provided 40 with an opening 10 adapted to permit a pan 11 to be slid into or removed from the bottom of the casing, this pan when in position being supported by bottom wall 12. The upper portion of pan 11 is disposed at an 45 angle to the front wall thereof, as at 11^a, and provides an air opening 13 extending the full width of the pan, and this front end portion is provided with spaced air inlet openings 14. The pan is adapted to contain 50 sawdust, grain chaff or any other suitable material which when ignited will burn 55

slowly and generate the smoke for curing meat and similar articles suspended within the casing from transverse rods 15 which are secured to angle strips 16 extending across 60 the side walls of the casing.

The smoke flows upwardly through the perforations of the lower plate 6 into the space or compartment 7 where it is thoroughly mixed with air flowing through 65 openings 8, this air serving to effectually cool the smoke so as to prevent undesirable heating of the articles being cured in the casing. To insure thorough mixing of the air and smoke, the perforations of the upper 70 plate 5 are staggered relative to the perforations of lower plate 6 thus insuring twisting or whirling motion of the smoke and slightly retarding upward flow thereof so as to effectually mix the smoke and the 75 cool air flowing through openings 8. This relatively cool mixture of air and smoke then flows through the perforations of plate 5 into the interior of the body of the casing and over and about the articles suspended 80 therein, the smoke finally escaping through an outlet pipe 15 at the top of the casing. This pipe is provided with a damper 16' of known type for regulating the flow of smoke and air through the pipe. 85

A smoking device constructed in this manner may be produced at small cost and is well adapted for domestic use. In addition, the burning material for producing the smoke is practically completely inclosed so 90 that danger of fire is reduced to a minimum. The screen coverings 9 for the air openings 8 serve to effectually prevent sparks or fire from escaping through these openings while permitting free entry of cool air into the 95 space or compartment 7 for the purpose stated.

What I claim is:

1. In a device of the character described, a casing, a pan fitting into the lower portion of said casing and adapted to contain fuel for generating smoke, said pan being provided with an air inlet opening for admitting air into pan across the top of the fuel, means for admitting air to the casing 100 above the pan, and means for retarding upward flow of the smoke and for causing mixing of this smoke with the air for cooling the smoke prior to its entry into the body of the casing. 105

2. In a device of the character described, a casing, a pan fitting into the lower por- 110

tion of said casing for containing smoke producing material, spaced perforated plates extending across the casing above the pan and disposed in spaced relation to each 5 other, said casing being provided with air inlet openings between the plates, and adjustable means for permitting escape of smoke from the casing.

3. In a device of the character described, 10 a casing, a pan fitting into the lower portion of the casing and adapted to contain

smoke producing fuel, two perforated plates extending across the casing above the pan, said plates being disposed in spaced relation and the perforations of one plate being staggered relative to the perforations of the other plate, the casing being provided with air inlet openings between said plates, and means for regulating the escape of smoke from the casing. 15

In testimony whereof I affix my signature.

FRANCIS MLEKUSH. 20
